PAYSON MARSH, OF LOS ANGELES, CALIFORNIA

SANITARY TOOTHBRUSH HOLDER

Application filed March 25, 1929. Serial No. 349,794.

The present invention relates to improvements in special receptacles and has reference more particularly to individual sanitary tooth brush holders.

5 One of the important objects of the present invention is to provide a tooth brush holder in which the bristles of a tooth brush are protected in a sanitary condition when not in use from foreign matter such as dust and the like.

One of the important objects of the present invention is to provide an individual sanitary tooth brush holder that includes a casing open at its respective ends and within which is arranged a brush head receiving unit, cooperating means being provided between the sides of the casing and the respective sides of said unit whereby the unit is caused to slide into and out of the casing by the action of the head 15 of the brush, the ends of the movable unit constituting closures for the open ends of the casing whereby to conceal the bristles of the brush within the casing when the brush is not in use.

20 Another important object of the invention is to provide a sanitary tooth brush holder that will at all times be positive and efficient in its operation, the same being simple in construction, inexpensive, strong and durable and further well adapted for the purposes for 25 which it is designed.

Other objects and advantages of the invention will become apparent from the following description when taken in connection 30 with the accompanying drawing.

In the accompanying drawings wherein like reference characters indicate corresponding parts throughout the same;

35 Figure 1 is a side elevation of the tooth brush holder embodying my invention showing the movable unit arranged entirely within the casing.

40 Figure 2 is a vertical sectional view thereof showing in dotted lines the position of the brush head of a tooth brush within the holder.

45 Figure 3 is a similar section showing the movable unit in a raised position and illustrating a tooth brush in the act of being

positioned in the holder to protect the bristles of the brush.

Figure 4 is a transverse section taken approximately on the line 4—4 of Figure 1 looking downwardly.

55 Figure 5 is a detail perspective view of the casing per se.

Figure 6 is a similar view of the movable unit drawn on an enlarged scale.

Figure 7 is a plan view of the blank from 60 which the movable unit is formed; and

Figure 8 is a view similar to Figure 3 showing the parts of the holder reversed whereby the brush is inserted in the holder from the bottom.

65 In the drawings wherein for the purpose of illustration is shown the preferred embodiment of my invention, the numeral 1 designates a substantially rectangular shaped casing that is open at its upper and lower ends, the same being formed from any suitable material such as celluloid, aluminum or the like. The free ends of the sheet material are folded over in overlapping relation and are secured together in any suitable manner. Formed in the sides of the casing 1 adjacent the upper edges thereof are the registering openings 2, the purpose of which will be 70 presently described.

75 Arranged for slidable movement within 80 the casing 1 is the substantially rectangular shaped brush housing or unit denoted generally by the numeral 3 in Figure 6. This housing or unit is also formed from the same material as the casing 1 and in Figure 7 of 85 the drawings, there is illustrated the blank from which this housing or unit is formed. The blank is designated by the reference character 4 and the dotted lines 5 indicate where the blank is folded to shape the same into the rectangular housing. The side walls of this housing are indicated by the reference character 6 while the top and bottom end portions are denoted by the reference characters 7 and 8 respectively.

90 The narrow side walls of the housing 3 are open and upon referring to Figure 6 it will be observed that the sides 6 are cut away as at 9 from the lower right hand corner to a point adjacent the top of the housing and 100

also to one side of the central portion of the housing. The upper portions of the sides 6 are cut away at the right hand side of the housing as at 10 and the cut away portions extend from the upper right hand corner inwardly and merge with the upper edge of the cut away portions 9. It will be noted that the cut away portions 10 are slightly curved whereas the cut away portions 9 are straight. 10 The purpose of this construction will be presently described in detail.

The sides 6 of the rectangular shaped housing or unit 3 are formed with longitudinally extending registering curved slots 11 that are 15 arranged adjacent the meeting points of the cut away portions 9 and 10 and operable within these slots 11 are suitable headed fastening elements 12 that extend through the openings 2 formed in the casing 1 and which openings 20 2 have communication with the respective curved slots 11. In Figure 4 of the drawings, there is clearly shown the manner in which the headed fasteners 12 are associated with the movable housing or unit 3 and the casing 1. 25

The lower right hand corner portion of the housing 3 is cut out as at 13 to accommodate the handle of the tooth brush. The casing 1 is of a length slightly greater than that of the 30 housing 3 and this is clearly indicated in Figures 1 and 2 of the drawings.

When the parts are arranged as shown in Figure 1, it will be observed that the movable unit or housing 3 is entirely confined within 35 the casing 1 and the upper and lower ends 7 and 8 of the movable unit 3 provide closures for the open upper and lower ends of the casing 1. By pushing upwardly on the bottom 8 of the movable unit 3, the same is caused 40 to move upwardly and out of the casing into the position shown in Figure 3 so that the upper portion of the movable unit 3 is disposed outwardly of the upper open end of the casing 1 and the cut out portion 9 will be disposed directly adjacent one of the narrow 45 sides of the casing and the pins or fastening elements will be disposed in the lower ends of the curved slots 11.

A tooth brush has its handle portion inserted downwardly between the left hand side of the casing 1 and the adjacent open side of the movable unit 3 so that the lower end portion of the handle will extend through the cut out portion 13 and when the lower 50 end of the handle projects beyond the lower end of the casing, this portion of the handle of the tooth brush is then grasped and a further downward pull is exerted on the brush so that the head of the brush will be entirely 55 within the casing and when the lowermost bristles strike the bottom walls 8, a further downward pull on the handle of the tooth brush will cause the movable unit 3 to move downwardly into the casing to the position 60 shown in Figure 2 so that the bristles of the 65

brush will be entirely concealed within the casing and the friction between the adjacent sides of the casing and the movable unit 3 will tend to hold the latter in a closed position with the ends of the movable unit or 70 housing 3 providing suitable closures for the open upper and lower ends of the casing. In this manner, the bristles of the brush will be protected against dust and other foreign matter when not in use. 75

When it is desired to use the brush, the handle of the brush is pushed upwardly causing the upper end of the brush head to strike the top wall 7 of the movable unit or housing 3 and said movable housing will move upwardly out of the casing to the position shown in Figure 3 by reason of the cooperating slots 11 and the fastening elements 12 and when the parts are arranged as shown in Figure 3, the tooth brush may then be readily and easily removed from the holder for use. 80

In Figure 8 of the drawings, I have shown a modification of the sanitary tooth brush holder wherein the parts are arranged upside-down that is to say the movable unit 3 is adapted to move out of the lower end portion of the casing instead of out of the upper end portion as in the previous description. In this modification, instead of the cut out portion 13 being disposed adjacent the cut away portions 9, said cut out portion is formed in the lower right hand corner of the movable unit as indicated at 14. Otherwise the parts are constructed in identically the same manner and the operation of this form of holder is thought to be readily obvious from the construction disclosed and therefore a detailed description of the same is believed unnecessary. 95

By constructing the casing 1 so that the same is of slightly greater length than the movable housing 3, provision is made for any bulge in the top or bottom of the housing or unit 3 that may result from usage with a view that the bulge will not cause unnecessary exposure or mar the appearance of the folder. 100

The provision of an individual sanitary tooth brush holder of the above-mentioned character will protect the bristles of a tooth brush when not in use and due to its simplicity, the holder can be readily and easily actuated for opening or closing the same by the action of the brush itself. An individual sanitary tooth brush holder of this character can be constructed and sold at a very low cost and the same will at all times be positive and efficient in carrying out the purposes for which it is designed. 115

While I have shown the preferred embodiment of my invention, it is to be understood that minor changes in the size, shape and arrangement of parts may be resorted to without departing from the spirit of the invention or the scope of the appended claims. 120

What I claim is:

1. In a tooth brush holder, a casing open at its respective ends, a housing for the brush head of a tooth brush slidably arranged within the casing, said housing being moved outwardly of the casing by the brush when the latter is moved in one direction, the housing being moved into the casing to conceal the brush head when the brush is moved in the opposite direction.
2. In a tooth brush holder, a casing open at its respective ends, a housing for the brush head of a tooth brush slidably arranged within the casing, said housing being moved outwardly of the casing by the brush when the latter is moved in one direction, the housing being moved into the casing to conceal the brush head when the brush is moved in the opposite direction, and coacting means between the casing and the movable housing for limiting the sliding movement of said housing.
3. In a tooth brush holder, a casing open at its respective ends, a housing for the brush head of a tooth brush slidably arranged within the casing, said housing being moved outwardly of the casing by the brush when the latter is moved in one direction, the housing being moved into the casing to conceal the brush head when the brush is moved in the opposite direction, said housing including side walls and top and bottom walls, said top and bottom walls providing closures for the respective upper and lower open ends of the casing when the housing is entirely within the casing.
4. In a tooth brush holder, a casing open at its respective ends, a housing for the brush head of a tooth brush slidably arranged within the casing, said housing being moved outwardly of the casing by the brush when the latter is moved in one direction, the housing being moved into the casing to conceal the brush head when the brush is moved in the opposite direction, said housing including side walls and top and bottom walls, said top and bottom walls providing closures for the respective upper and lower open ends of the casing when the housing is entirely within the casing, the sides of the movable housing being formed with curved slots, means carried by the adjacent sides of the casing for operation within the respective curved slots to limit the sliding movement of the housing.
5. In a tooth brush holder, a casing open at its respective ends, a housing for the brush head of a tooth brush slidably arranged within the casing, said housing being moved outwardly of the casing by the brush when the latter is moved in one direction, the housing being moved into the casing to conceal the brush head when the brush is moved in the opposite direction, said housing including side walls and top and bottom walls, said

top and bottom walls providing closures for the respective upper and lower open ends of the casing when the housing is entirely within the casing, the sides of the movable housing being formed with curved slots, means carried by the adjacent sides of the casing for operation within the respective curved slots to limit the sliding movement of the housing, the sides of the housing being cut away at one edge in a predetermined manner whereby the outer end portion of the housing is disposed out of alignment with the casing when the housing is moved to its outermost position.

In testimony whereof I affix my signature.

PAYSON MARSH.
